Attys.

UNITED STATES PATENT OFFICE.

EDWARD H. ANGIER, OF FRAMINGHAM, MASSACHUSETTS.

PACKAGE.

1,385,165.

Specification of Letters Patent. Patented July 19, 1921.

Application filed October 7, 1920. Serial No. 415,234.

To all whom it may concern:

Be it known that I, EDWARD H. ANGIER, a citizen of the United States, and a resident of Framingham, county of Middlesex, 5 and State of Massachusetts, have invented an Improvement in Packages, of which the following description, in connection with the accompanying drawings, is a specification, like characters on the drawings representing like parts.

This invention relates to packages wherein a commodity is inclosed by a wrapping or covering of paper or the like and has to do particularly with a package wherein the 15 thing inclosed does not present a smooth surface but one having interstices. An example is a bale or bundle of a number of articles which do not exactly fit together.

As an example of my invention I have in 20 the accompanying drawing shown in perspective with a part broken away a package consisting of a pile of tires.

Referring to the drawing I there show a package or bale comprising a plurality of 25 ring shaped bodies 5 such as tires piled one on the other. Because of the rounded exterior form of the tires they present between them grooves 7 extending circumferentially of the package. The tires are inclosed in a 30 suitable covering or wrapping which is preferably formed of paper provided with resilient embossments 9 conveniently formed by crinkling the paper in well known manner. Paper prepared in this fashion is expansible 35 locally and can adapt itself to the form of the commodity inclosed, the embossments partially expanding against their resiliency to fit. Herein this wrapping is in the form 40 of a narrow strip 11 applied helically in a number of overlapping turns, this form of wrapping being particularly adapted to ring shaped articles such as tires and providing for a closer application of the covering than is possible by the use of sheets.

To more firmly secure the covering about 45 the pile of tires 5 and incidentally to position the various turns of helical wrapping I may employ suitable binder strips 13, preferably consisting of crinkled paper, which 50 may be applied to encircle the package at the locations of the grooves 7 and which tighten the main wrapping around the individual articles by tensioning the material and drawing it down into the groove 7 as indicated clearly at the right of the figure. The strips 13 may be adhesively secured as

indicated by the showing of the adhesive coating 15 on the portion of a strip shown turned back at the left of the figure, thus serving to hold the parts of the wrapping 60 firmly in place. If, as is preferably the case, the wrapping is composed of crinkled or similarly prepared paper the local expansion of the paper permits it to be closely adapted to the individual articles inclosed 65 in this manner. The use of crinkled paper for the binding strips, furthermore, permits them to cup up in the manner shown at the right of the figure to adapt themselves to the groove 7 and to press the main binding 70 firmly into contact with the adjacent parts of the tires.

I herein refer to a plurality of articles. Obviously, however, certain individual articles may be of multiple form. Thus for 75 example a dual truck tire is similar to two single tires set side by side. To attempt, however, to refer to the contents of the package by generic terms would, however, have led to such abstract language as to conceal 80 rather than explain the essential features of my invention and I have therefore preferred to use more perspicuous terms in an exemplary sense. I have further referred to the binder strips 13 in the plural. 85

In a package of two tires, for example, there would be one groove 7 and one strip 13.

Having described in detail the illustrative embodiment of my invention shown in the accompanying drawing, what I claim as new 90 and desire to secure by Letters Patent I shall express in the following claims.

Claims:

1. A package comprising a plurality of assembled articles providing grooves between them, a wrapping inclosing the articles and binders encircling the package and tensioning the wrapping by drawing it down into said grooves. 95

2. A package comprising a plurality of assembled articles providing grooves between them, a wrapping of helically applied strip inclosing the articles and binders encircling the package and tensioning the wrapping by drawing it down into said 105 grooves.

3. A package comprising a plurality of assembled articles providing grooves between them, a wrapping of helically applied strip inclosing the articles and adhesively 110 secured binder strips applied transversely of the turns of the helix and tensioning the

same about the individual articles by drawing them down into said grooves.

4. A package comprising a pile of ring-like articles presenting interjacent circumferential grooves, a paper wrapping inclosing the same having partially expanded resilient embossments and bands of like ma-

terial overlying the wrapping at said grooves and tensioning the same about the individual articles.

In testimony whereof I have signed my name to this specification.

EDWARD H. ANGIER.
